(57) **CLAIM**

The ornamental design for a mirror for an automobile, as shown and described.

DESCRIPTION

FIG. 1 is a front perspective view of a mirror for an automobile of my new design;

FIG. 2 is a right side view thereof;

FIG. 3 is a left side view thereof;

FIG. 4 is a rear view thereof;

FIG. 5 is a front view thereof;

FIG. 6 is a top plan view thereof; and,

FIG. 7 is a bottom plan view thereof.

My design includes the mirror image of the embodiment depicted.
